UNITED STATES PATENT OFFICE.

EDWARD L. MEISINGER, OF CLARION, PENNSYLVANIA.

VACUUM CARBURETOR.

Application filed January 19, 1924. Serial No. 687,332.

To all whom it may concern:

Be it known that I, EDWARD L. MEISINGER, a citizen of the United States, residing at Clarion, in the county of Clarion and State 5 of Pennsylvania, have invented certain new and useful Improvements in Vacuum Carburetors, of which the following is a specification.

The invention relates to improvements in 10 a vacuum carburetor.

It is an object of the invention to provide a carburetor construction having combined therewith in a single casting a vacuum tank, thereby providing a structure where 15 the vacuum tank and the carburetor comprise a single unit.

The invention more specifically comprehends a vacuum carburetor of this character wherein a single casting is formed to 20 provide the float chamber of a carburetor and the vacuum tank with an integral partition in said casting, forming such chamber and tank. The invention further consists of an improved float operated valve 25 for controlling the suction in the float chamber whereby said valve will always remain in either an entirely open or an entirely closed position and will not occupy intermediate positions.

30 In the accompanying drawings, I have shown the preferred embodiment of my invention in which

Fig. 1 represents a side elevation,

Fig. 2 a top plan view,

35 Fig. 3 a transverse section,

Fig. 4 a sectional view from the check valve,

Fig. 5 a transverse sectional view and,

40 Figs. 6, 7, 8, 9 and 10 detail views of the valve operating mechanism.

Referring now more particularly to the drawings, wherein like reference characters indicate corresponding parts, numeral 1 designates a connection containing the mixing chamber 3, the connection 1 being secured to the usual intake manifold of an engine. This connection at its lower end is flanged at 4 and receives a combined carburetor and vacuum tank designated by the 45 character *a*. Fastening screws 5 are used for attaching this tank to the connection 1.

The combined vacuum tank and carburetor is composed of a single casting of metal, having a vacuum tank 6 at one side, and 55 a constant fuel level reservoir 7 at the opposite side. The vacuum tank is separated

from the fuel reservoir by the integral partition 8 and the integral circular carbureting or mixing chamber 9, as clearly shown in Figure 5. In describing this device, the 60 vacuum tank will be first described in detail and then its connection to the constant level fuel reservoir and the feeding means from said reservoir to the mixing chamber of the carburetor.

The vacuum tank is, as before stated, cast integral with the chamber 7. This tank is provided with a removable closure 10 shown as having a downwardly extending flange 11 united to the top of the vacuum chamber 6 by screws 12' or the like. Communicating with the vacuum tank, there is a suction pipe 12 leading to the connection 1 above the throttle valve 2 and its opposite end terminating within the closure 11. There 75 is also a vent opening 13 passing through the nipple 14 which nipple is secured to the cover 10, the vent communicating with the atmosphere in the usual manner. A gaso- 80 lene conveying pipe 15 leads from the gaso- lene supply tank of the motor vehicle, usually lower than the level of the vacuum tank, this pipe being secured to cover plate 11 by the fastening nut 16. In use, it is obvious that during the operation of the en- 85 gine, a suction is created through the line 12, if this line is open and the vent opening closed. In accordance with my invention, I provide valves for controlling said vent opening and said suction line responsive to 90 the liquid level of gasolene in the vacuum tank 6. With this end in view, I provide a float 17 which is connected to an arm 18 pivoted between the spaced downwardly 95 extending brackets 19 having a connecting lower web 20. When the float valve is in the full line position shown in Fig. 5 there is sufficient fuel in the vacuum tank 6, hence the suction pipe 12 is closed and the vent opening 13 open. 21 designates the suction 100 pipe valve, which is a valve of the usual construction used in vacuum tanks, while 22 designates the vent passage controlling valve, these valves being pivotally connected to the links 23 at each end thereof, the links 105 at their center are pivoted to a depending bracket 24 so that as the links rock the valves will likewise move, and when one valve is closed the other valve must be opened. Pivots connected to the links 23 110 there are arms 26 which are suspended by the said bracket 24, the free end of the arms

entering a space between supporting standards for the float valve 17. Pivotally connected to said arms 26, there are the trip arms 27 pivotally connected at their lower ends to the pivoted rod 8 carrying the float 17. As the float drops it naturally draws downwardly the trip arms 27 and these arms likewise move the pivoted arms 26 in a downward direction. A lateral pin 10 constitutes the pivotal connection between the arms 26 and 27 and said pin at its outer end receives one end of the coil springs 29, the opposite ends of said springs being connected to the pin 30 which passes through and 15 joins the links 23 to the valve 21. It is apparent that during the downward movement of the arms 26, the free ends of said arms are guided by the standard 19. When the float has reached a position as shown in Fig. 20 8, the arms 26 have been drawn downwardly so that the coil springs 29 are below the point of pivot of the rocking links 23. The moment that such springs extend beyond or to one side of this pivoted connection, the 25 springs obviously exert an influence on the links and serve to draw these links downwardly with a snap action. This means that the suction controlling valve 21 is wide open and the vent valve 22 entirely closed. In 30 other words, the snap action of the spring will not permit either one of the valves to be partially open or closed. They must be entirely open or entirely closed. As the float rises and moves in an upward path it, 35 of course, raises with it the trip arms 27, which lifts the arms 26 and as soon as said arms reach a position above the pivoted support for the links 23, the coil springs 29 will exert a counter influence on these links 40 and will snap the links into the positions shown in Fig. 5 at which time the suction controlling valve 21 is entirely closed and the vent valve 22 open, inasmuch as the vacuum tank is full of fuel and it is desirable to maintain an atmospheric pressure 45 therein. The position of the float valve will, of course, fluctuate during the use of the engine, that is, it will drop when substantial quantities of fuel are being used and will 50 remain in a position to permit the suction pipe to be opened as long as the tank is not filled. When the tank fills, however, this suction valve is closed and the vent valve 55 opened.

The fuel in the vacuum tank 6 constitutes a reservoir supply for the fuel feeding tank 7. The partition 8 in the casting is formed at its lower end near each side with diverging walls and between said diverging walls 60 8' are plugs 9' detachably inserted by means of fastening screws 11'. These plugs each have a transverse bore 10' and the diverging walls of the partition are also ported. The plugs 9' each carry a flap valve 12' as 65 clearly shown in Fig. 4. Fuel from the vac-

uum chamber 6 flows through the ports 10' and into the constant level supply chamber 7 of the carburetor. The level of the fuel in this chamber will remain the same as the fuel level in the vacuum tank 6. When the 70 chamber 7 is filled the flap valves 12' will, of course, close because of the equalization of pressure and will remain closed until the supply in the chamber 7 is lower than the fuel level in the vacuum tank 6. When this 75 condition is reached the flap valves open for the passage of fuel to the chamber 7.

The central opening 9 formed in the casting is adapted to receive an inserted venturi or cone-shaped member 31 inserted therein 80 to provide a jacket 32 adapted to receive heating gases from the engine to assist in vaporizing the fuel. The reduced opening through this venturi 31 seats an air valve 33 having a shaft or stem 34 passing 85 through a bracket 35, the lower end of said stem receiving a coil spring 36, the tension of which is regulated by a nut 37. The stem intermediate its ends and where it passes through the bracket 35 is rectangular 90 in shape. It is apparent that the inserted tube or venturi 31 is open at its lower end and that the valve 33 controls the quantity of air admitted to the mixing chamber 3. Fuel is supplied to the mixing chamber 95 through the high and low speed fuel feeders 39 and 40, respectively. These feeders are controlled by the valves 41 and 42 whereby the richness of the mixture may be regulated. The low speed feeder 40 communicates with a conduit 43 opening at one end beneath the air valve 33 and at its opposite end in the mixing chamber 3, while the fuel feeder 39 enters the mixing chamber at a point directly above the air valve 33. 100

Having thus described the invention, the operation may be briefly stated as follows:

When the engine is running and fuel is being drawn into the vacuum tank 6, the float valve 17 has dropped to a position 110 whereupon the arms 26 are lowered and the springs 29 have snapped the links 23 to a position to open the valve 21 and close the vent valve 22. This permits the creation of a vacuum in the tank 6, drawing the fuel thereto through the feeding pipe 15. When the tank 6 becomes filled, the float raises and this, of course, raises the arms 26 to a position where the springs 29 shift the position 115 of the links 23 and open the valve 21 and close the valve 22. The fuel admitted to the vacuum tank 6 flows over and into the constant level fuel reservoir 7 through the ports 10' in the plugs 9' and the flap valves 12' maintain the level in the two chambers uniform. The suction of the engine draws the fuel from the fuel chamber 7 through the feeding pipes 39 and 40 where it mixes with the required quantity of air admitted to the mixing chamber 3 by the opening of the 120 125 130

air valve 33. This operation continues, it being apparent that both the carburetor and the vacuum tank are formed in a unitary structure and from a single casting.

5 Having thus described the invention, what I claim is:

1. A combined carburetor and vacuum tank having a vacuum chamber and a fuel feeding chamber formed from a single metallic casting, said casting having an integral central partition dividing said chambers, said partition at substantially its center being formed with an enlarged air passage for the passage of air between said chambers, a suction controlled valve in said air passage, float controlling means in the vacuum chamber for controlling the admission of fuel thereto and a suction connection between said chamber and an engine manifold, the walls of said partition diverging toward the bottom of the casting, there being fuel feeding openings in said separated walls for delivering fuel from the vacuum chamber to said fuel feeding chamber, a removable substantially triangular plug member provided with an opening in line with the openings in said walls of said partition, a valve controlling said opening carried by said plug and removable therewith, and means for feeding fuel through

said fuel chamber to said central air passage above the air valve therein, a mixing chamber adjacent said air valve, and a throttle valve in said mixing chamber.

2. In an article of the character described, the combination with an enlarged casting, said casting being formed with an integral vacuum chamber and fuel feeding chamber, an integral substantially central partition dividing said chambers and intermediate its ends being formed to provide a substantially circular carburetting chamber, an air valve in said chamber, a throttle valve therein, a float controlled valve in the vacuum chamber for controlling the admission of fuel thereto, a suction connection between said chamber and an engine manifold, a fuel feeding nozzle leading from said fuel chamber to said carburetting chamber, said partition at its lower end being provided with diverging walls, aligned apertures in said walls, a removable plug of substantially triangular cross section provided with a port disposed between said diverging walls of the partition, a check valve carried by said plug and removable therewith as a unit, and means for retaining said plug in position.

In testimony whereof I affix my signature.

EDWARD L. MEISINGER.
